UNITED STATES PATENT OFFICE.

WALTER S. RUNNELS, OF KALAMAZOO, MICHIGAN.

SAWING AND TRIMMING MACHINE.

Application filed November 8, 1923. Serial No. 673,624.

To all whom it may concern:

Be it known that I, WALTER S. RUNNELS, a citizen of the United States, residing at the city and county of Kalamazoo, State of Michigan, have invented certain new and useful Improvements in Sawing and Trimming Machines, of which the following is a specification.

This invention relates to improvements in sawing and trimming machines.

My improved sawing and trimming machine is especially designed by me for use in sawing and trimming electrotype, stereotypes, linotypes and half-tones and the like and I have illustrated my improvements as I have embodied in such a machine. My improvements are, however, readily adapted for use in other relations.

The main objects of this invention are:

20 First, to provide in a structure of the class described an improved work clamping means whereby the work may be effectively clamped and supported for the sawing and other operations thereon.

25 Second, to provide an improved work gauge which may be quickly and accurately adjusted.

30 Objects pertaining to details and economies of construction and operation of my improvements, will definitely appear from the detailed description to follow.

I accomplish the objects of my invention by the devices and means described in the following specification. The invention is clearly defined and pointed out in the claims.

35 A structure which is a preferred embodiment of my invention is clearly illustrated in the accompanying drawing forming a part of this application, in which:

40 Fig. I is a plan view of a structure embodying the features of my invention, the work being indicated by dotted lines.

Fig. II is a detail rear perspective view of the work gauge.

45 Fig. III is a detail plan view of the work gauge.

Fig. IV is a fragmentary side elevation showing details of the work clamping means.

50 Fig. V is a detail side elevation corresponding to that of Fig. IV in which the pawl of the clamping mechanism is shown in disengaged position.

Fig. VI is a detail section on a line corresponding to line 6—6 of Figs. I and IV.

55 Fig. VII is a detail section on a line corresponding to line 7—7 of Fig. IV.

Fig. VIII is a detail section on a line corresponding to line 8—8 of Fig. I.

Fig. IX is a detail section on a line corresponding to line 9—9 of Fig. I showing details of the gauge adjusting means.

In the drawing similar reference numerals refer to similar parts throughout the several views and, the sectional views are taken looking in the direction of the little arrows at the ends of the section lines.

Referring to the drawing, 1 represents the table which is provided with a way 2 for the carriage 3. Mounted on the front end of this carriage is a gauge bar 4, the bar overlying the table and being slidable thereon as the carriage 3 is moved back and forth.

On this gauge bar 4 I mount a rack bar 5 for longitudinal sliding adjustment, the rack bar having slots 6 at its ends engaging the screws 7 thereby supporting the bar for limited longitudinal movement. To indicate scale 8 is secured to the front of the bar 4 parallel with the rack bar. This scale is provided with indicia facilitating the adjustment of the movable gauge member 9 which is slidable to gauge and support the work indicated by dotted lines at 10.

This adjustable gauge member 9 is provided with a locking dog 11 held in yielding engagement with the rack by means of the spring 12. By this arrangement the gauge member 9 may be freed from the rack permitting free sliding adjustment of the gauge member, the block 11 holding the gauge in its adjusted position relative to the rack 5.

The rack bar is longitudinally adjusted by means of the lever 13 which is pivoted to the rack bar at 14 and provided with a lug 15 engaging the cam slot 16 in the segment-like extension 17 of the base bar 4. This lever overhangs the end of the segment and is provided with a detent 18, see dotted lines in Fig. III, coacting with a series of holes 19 in the edge of the segment, thereby retaining the lever in its adjusted position.

The pivot 14 is in non-concentric relation to the cam groove so that as the lever is swung on its pivot the rack bar is moved longitudinally. The segment is provided with scale indicia 20 facilitating the accurate adjustment.

After the rapid and relatively coarse adjustment by means of the manual manipulation of the gauge member the fine adjustment may be accomplished by means of the

lever 13, the bar 5 and the gauge member 9 being adjusted as a unit.

To effectively clamp the work to the carriage, the gauge constituting an abutment 5 against which the work is clamped, I provide a clamp or vise comprising a ratchet bar 21 which is pivoted at 22 to the rear end of the carriage slide 3 so that it may be swung up out of the way permitting freedom of operation in the machine, the front end of the ratchet bar being detachably secured to the carriage by means of the screw 22'. In operation the ratchet bar is normally fixed to the table but it may be swung up out 10 of the way by releasing the screw 22'.

The bar-like clamping member 23 is supported in the blocks 24 and 25 which constitute supports for the ends of the ratchet bar 21.

20 I provide a pawl 26 which is in the form of a block having offset pawl teeth 27 adapted to be engaged with the ratchet teeth of the ratchet bar as shown in Fig. IV. This pawl is longitudinally slotted at 27' to receive the screw 28 so that the pawl is supported for pivotal and sliding movement on the clamping bar. A coiled spring 29 is arranged to engage the screw 28, thereby yieldingly supporting the pawl.

30 I provide an adjusting lever 29 which has threaded engagement with a fulcrum block 30 pivoted at 31' on the clamping bar, the pivot being in front of the pawl. The inner end of this lever is adapted to engage the recess 32 in the front end of the pawl so that the lever may be tilted to engage and disengage the pawl and rotated to apply clamping stress to the clamping bar. When the pawl is freed from the ratchet bar the clamping bar may be moved freely to or from the work, 35 the lever then being in an elevated position. The weight of the lever tends to engage the pawl so that when it is desired to adjust to clamping position the clamping bar is moved 40 against the work by means of the lever, the lever swung downwardly or permitted to fall to engage the pawl and the lever rotated to apply clamping stress.

45 My improved clamping means is very simple in structure, easily adjusted, is powerful and is strong and durable. It has the advantage of rapidity of adjustment as has also the means for adjusting the gauge. It will be understood that the gauge constitutes 50 an abutment against which the work is clamped by the work clamping means.

I have illustrated and described my improvements in an embodiment which I have found very practical. I have not shown the 55 means for driving the saw indicated at 33, the saw being supported on a swinging support indicated by dotted lines at 34 and the adjustment of this support being through the lever 35. These parts, however, form no 60 part of my present invention and are, there-

fore, not illustrated or described in detail herein.

Having thus described my invention what I claim as new and desire to secure by Letters Patent is:

70 1. In a structure of the class described, the combination of a ratchet bar, a clamping bar slidably associated with said ratchet bar, a pawl having a longitudinal slot therein, a pivot on said clamping bar engaging said slot whereby the pawl is supported for pivotal and longitudinal movement, a spring arranged to urge said pawl yieldingly forward on its said pivot, an adjusting lever, and a fulcrum block pivotally mounted on said clamping bar in front of said pawl, said lever being threaded into said fulcrum block 75 to engage the front end of said pawl whereby the pawl may be engaged and disengaged with the ratchet bar by a swinging movement of the lever and clamping stress applied to the clamping bar by rotative movement of the lever when the pawl is engaged with the ratchet bar, the clamping bar being free for adjustment when the pawl is disengaged from the ratchet bar.

80 2. In a structure of the class described, the combination of a ratchet bar, a clamping bar slidably associated with said ratchet bar, a pawl mounted on said clamping bar for pivotal and sliding movement, a spring arranged to urge said pawl yieldingly forward, an adjusting lever, and a fulcrum block pivotally mounted on said clamping bar in front of said pawl, said lever being threaded into said fulcrum block to engage 85 the front end of said pawl whereby the pawl may be engaged and disengaged with the ratchet bar by a swinging movement of the lever and clamping stress applied to the clamping bar by rotative movement of the lever when the pawl is engaged with the ratchet bar, the clamping bar being free for adjustment when the pawl is disengaged 90 from the ratchet bar.

95 3. In a structure of the class described, the combination of a relatively fixed ratchet bar, a clamping member slidably associated with said ratchet bar, a pawl mounted on said clamping member for pivotal and sliding movement, a spring arranged to urge 100 said pawl yieldingly forward, an adjusting lever having a pivotal and threaded connection with said clamping member engaging the front end of said pawl whereby the pawl may be engaged with and disengaged from the ratchet bar by a swinging movement of the lever and clamping stress applied to the clamping bar by a rotative movement of the lever when the pawl is engaged with the ratchet bar, the clamping bar being free for 105 adjustment when the pawl is disengaged from the ratchet bar.

110 4. In a structure of the class described, the combination of a table, a ratchet bar hinged 115

at its rear end to said table, means for detachably securing the front end of said ratchet bar to said table, a clamping bar slidably associated with said ratchet bar, a pawl 5 adjustably mounted on said clamping bar to coact with said ratchet bar, and an adjusting lever having a pivotal and threaded connection to said clamping bar and coacting with said pawl so that the pawl may be engaged with and disengaged from said ratchet bar by a swinging movement of the lever and clamping stress applied to the clamping bar by rotative movement of the lever when the pawl is engaged with the ratchet bar.

15 5. In a structure of the class described, the combination of a table, a ratchet bar hinged at its rear end to said table, means for detachably securing the front end of said ratchet bar to said table, a clamping bar 20 slidably associated with said ratchet bar, a pawl adjustably mounted on said clamping bar to coact with said ratchet bar, and an adjusting lever having a pivotal and threaded connection to said clamping bar and coacting with said pawl so that the pawl may be engaged with and disengaged from said ratchet bar by a swinging movement of the lever and clamping stress applied to the clamping bar by rotative movement of the lever when 25 the pawl is engaged with the ratchet bar.

6. In a structure of the class described, the combination of a ratchet bar, a clamping bar slidably associated with said ratchet bar, a pawl adjustably mounted on said clamping 30 bar to coact with said ratchet bar, and an adjusting lever having a pivotal and threaded connection to said clamping bar and coacting with said pawl so that the pawl may be engaged with and disengaged from said ratchet bar by a swinging movement of the lever and clamping stress applied to the clamping bar by rotative movement of the lever when the pawl is engaged with the ratchet bar.

45 7. In a structure of the class described, the combination of a relatively fixed ratchet bar, a clamping bar slidably associated therewith, a pawl adjustably mounted on said clamping bar to coact with said ratchet bar, and 50 an adjusting lever having a pivotal and threaded connection to said clamping bar and coacting with said pawl so that the pawl

may be engaged with and disengaged from said ratchet bar by a swinging movement of the lever and clamping stress applied to the 55 clamping bar by rotative movement of the lever when the pawl is engaged with the ratchet bar.

8. In a structure of the class described, the combination of a gauge comprising a base 60 bar, a rack bar mounted for longitudinal sliding adjustment on said base bar, an adjustable gauge member slidably mounted on said rack bar and provided with a dog coacting therewith whereby the gauge member 65 is secured in its adjusted positions, said base bar being provided with gauge indicia operatively associated with said adjustable gauge member, a segment on the outer end of said base bar provided with a cam groove, 70 and a rack bar adjusting lever pivotally connected thereto and provided with a lug engaging said cam groove in said segment, said segment being provided with gauge indicia 75 operatively associated with said lever.

9. In a structure of the class described, the combination of a gauge comprising base 80 bars, a rack bar mounted for longitudinal sliding adjustment on said base bars, an adjustable gauge member slidably mounted 85 on said rack bar and provided with a dog coacting therewith whereby the gauge member is secured in its adjusted positions, said base bar being provided with gauge indicia operatively associated with said adjustable gauge member, and means mounted on said base bars for slidably adjusting said rack bar provided with coacting gauge indicia.

10. In a structure of the class described, the combination of a gauge comprising a 90 rack bar mounted for longitudinal adjustment, an adjustable gauge member provided with a dog coacting with said rack bar, said adjustable gauge member having gauge 95 indicia operatively associated therewith, and means for longitudinally adjusting said rack bar comprising a cam and a lever operatively associated therewith and pivotally connected to said rack bar, said rack bar adjusting means having gauge indicia operatively associated therewith.

In witness whereof I have hereunto set my hand.

WALTER S. RUNNELS.
